UNITED STATES PATENT OFFICE.

ELIEL L. SHARPNECK, OF BOSTON, MASSACHUSETTS.

STARTING DEVICE FOR INTERNAL-COMBUSTION MOTORS.

942,467.

Specification of Letters Patent. Patented Dec. 7, 1909.

Application filed February 6, 1909. Serial No. 476,579.

To all whom it may concern:

Be it known that I, ELIEL L. SHARPNECK, of Winthrop, in the county of Suffolk, State of Massachusetts, have invented certain new and useful Improvements in Starting Devices for Internal-Combustion Motors, of which the following is a full, clear, and exact specification, reference being had to the accompanying drawings, forming part thereof.

This invention relates to improvements in internal combustion motors and has reference particularly to devices designed to effect the starting of such motors.

15 The object of this invention is to provide means for discharging into an internal combustion motor a charge of fluid under pressure to effect the initial movement of one or more of its pistons.

20 The invention consists in such peculiar features of construction and combinations of parts as shall hereinafter be more fully described and pointed out in the claims.

Figure 1, represents a side elevation of 25 parts of an internal combustion motor of well known construction shown in relation to the dash board of a vehicle and as combined with the improved starting mechanism. Fig. 2, represents a reverse view of 30 some of the parts shown in Fig. 1. Fig. 3, represents a front elevation of the controlling lever and its holding means. Fig. 4, represents a side view of the same. Fig. 5, represents an enlarged sectional view, taken 35 on line 5—5 Fig. 1, of a portion of the exhaust. Fig. 6, represents a vertical sectional view of Fig. 5. Fig. 7, represents a sectional view, taken on line 7—7 Fig. 2, of the controlling valve for the supply pipe of the 40 starting device with its actuating cam.

Similar characters of reference designate corresponding parts throughout.

As shown in the drawings 9 represents the casing of any well known motor mechanism 45 designed to be operated by fluid compression and particularly any well known internal combustion engine having one or more cylinders each furnished with the usual movable piston. Suitable gaseous fluid being 50 supplied to said cylinders through pipes 10 and 11 and the unconsumed gases being delivered from said cylinders to the pipes 12 and 13 to the exhaust pipe 14.

In carrying this invention into practice I 55 provide the exhaust pipe or chamber 14 with

the branch outlet 15 having a valve seat at its inner end. Journaled in bearings in the wall of the chamber 14 is the shaft 16 having at its inner portion the beveled edge valve 17 designed, at times, to close said 20 chamber 14 and furnished with the valve stem 18 carrying the conical valve 19 adapted, when the valve 17 is in the open position, to close the outlet 15. The outer end of the shaft 16 is supplied with the collar 20 having the cam face 21 and arm 22 and the arm 23, normally retracted by spring 24, secured to said arm and to a fixed portion of the chamber 14, whereby the valves 17 and 19 are normally positioned as shown in Fig. 6. 25

The outlet 15 is preferably connected with the casing 25 of any well known check valve and said casing 25 is connected by the pipe 26 with the pressure tank 27 located in any desired position and having the outlet 28 30 which communicates through the valve chamber 29 with the pipe 30 connected with the fluid delivery pipe 11. Valve chamber 29 is furnished with the usual check valve 31 having the spring retracted valve stem 32 35 the outer end of which is rounded somewhat. In addition to the outlet pipe 28 the tank 27 is preferably furnished with the pipe 33 communicating with the well known pressure gage 34 located at any convenient point 40 but herein shown as mounted on the dash board D of a vehicle.

Mounted on the dash board D, or on any suitable support, is the plate 35 having the curved rack 36 furnished with notches 37, 38 and 39. Journaled in axial relation to the rack 36 is the shaft 40 having the lever handle 41 furnished with the spring latch 42, designed to engage in said notches 37, 38 and 39, and, at points respectively adjacent 45 the valve stem 32 and the exhaust chamber 14, with the cam 43 and with the arm 44 having a roller bearing which is located between the cams 21 and arm 22 of collar 20. 50

When the motor is operating under normal conditions the parts are in the positions shown in full lines. If now the operator desires to store fluid under compression, for use in restarting, opportunity is taken at a time when the motor is not unduly loaded 55 as, in case of a vehicle driven by said motor, when such vehicle is descending an incline, to shut off the sparking mechanism whereupon the motor will run, by momentum, as a compressor and will force the compressed 60

gaseous fluid out through the exhaust 14. After a few operations of the motor all products of previous combustion will be forced out through the exhaust 14 and the 5 temperature of said exhaust chamber, which under normal operating conditions has been raised, will be reduced considerably. The operator now swings the handle lever 41 to the notch 37, marked "Pump," and the latch 10 engages said notch and lever in that position while the rotation of shaft 40, by such movement of arm 41 swings the arm 44 the roller bearing of which acting against cam 21 effects the swinging of said cam, against the 15 action of its spring 24, and the partial rotation of the shaft 16 to bring valves 17 and 19 to the positions shown in dotted lines in Fig. 6 whereupon the compressed gaseous fluid forced outward by the operation of the 20 motor will pass through the outlet 15, check valve 25 and pipe 26 to tank 27. When the gage 34 indicates that the pressure within the tank 27 is suitable the operator swings handle 41 back to notch 39 and thus releases 25 cam 21 which swings back to its normal position under the retractive strain of the spring 24 to effect the closing of valve 19 against its seal and to open valve 17. At this time the check valve in casing 25 will 30 prevent the escape of gaseous fluid through pipe 26 and outlet 15 while the valve 31 will prevent the escape of such gas through pipe 30. The operation of restarting the motor is extremely simple and is accomplished by 35 swinging lever handle 41 to notch 38 whereby the shaft 40 is rotated to bring its cam 43 to be against the end of the valve stem 32 and to press inward said stem and open valve 31 to permit the passage of the gaseous fluid, stored in tank 27, through pipes 40 30 and 11 to the motor 9 to effect the initial movement of said motor until it reaches a point at which the charge of fluid is exploded. The subsequent operation of the 45 motor being in the ordinary manner. It is obvious that this starting device can be applied to a stationary motor of the nature described.

Having thus described my invention I

claim as new and desire to secure by Letters Patent.

1. The combination with an internal combustion motor having an exhaust furnished with two outlets, of a valve movably mounted in said exhaust, for controlling the flow of fluid therethrough, and a second valve actuated by the opening movement of said first mentioned valve to close one of said outlets. 55

2. The combination with an internal combustion motor having an exhaust pipe furnished with a branch outlet, and a storage tank connected with said outlet, of a shaft journaled in said exhaust pipe and having a valve member designed to close said branch outlet, and means for operating said valve 65 shaft. 60

3. The combination with an internal combustion motor having an exhaust furnished with a branch outlet, a tank connected with said outlet and with the fluid supply of said motor by a pipe having a normally closed valve, of a duplex valve within said exhaust and having an actuating member extending from said exhaust, and rotatable means for 70 operating said valve actuating means. 75

4. The combination with an internal combustion motor having an exhaust furnished with a branch outlet having a valve seat, a storage tank connected with said branch outlet and by a pipe with the fluid supply of 80 said motor, a spring closed valve in said pipe, a shaft journaled in said exhaust and having a valve, within said exhaust, and furnished with a valve member adapted to close the valve seat of said branch outlet, a spring retracted arm on the outer end of said valve shaft and having a cam, of a shaft journaled in bearings and having means adapted to act respectively against the valve stem of the supply valve and against said 85 cam of the exhaust valve shaft arm to actuate said members against the pressure of their respective springs. 90
